ISADOR LEO FRIEDLAENDER AND STEPHEN J. MARX, OF DETROIT, MICHIGAN.

ANTISKID FREIGHT-ANCHORING DEVICE FOR FLAT CARS.

Application filed March 29, 1926. Serial No. 98,224.

Our invention relates to an anti-skid freight anchoring device for flat cars shown in the accompanying drawings and more particularly described in the following specification and claims.

The primary object of our invention is an anchoring device employed in the shipment of relatively large boxed or crated freight upon flat cars and while of simple 10 and inexpensive construction, serves to effectually anchor and prevent skidding of boxed freight upon a car deck;—the device is adapted also for anchoring superposed boxes or crates.

15 A further object of the invention is to provide a device which may not only be spiked to the deck of the car but will automatically embed itself in the car deck and walls of the boxes or crates due to the weight 20 of the latter thereon.

A further object is to provide a device adapted to embed itself in the walls of superposed boxes or crates when interposed between the walls of the boxes.

25 A further object of the invention is to provide a construction adapted to receive the ends of metal straps overlapping the boxes and connected to a plurality of the devices spiked to the deck of the car adjacent to each side and ends of the boxes or crates loaded directly upon the car deck;—the 30 ends of the straps being "sealed" in the usual manner thereby anchoring the freight to the car deck and protecting it against 35 unlawful tampering.

40 A further object is to provide for connecting by metal straps the devices spiked to the car deck with others inserted between the walls of superposed boxes,—the straps overlapping the upper walls for engagement with like members located on the opposite sides and ends of the boxes or crates.

45 With the foregoing and other objects in view which will appear as the description proceeds the invention further resides in the details of construction hereinafter described and claimed it being understood that changes may be made in the precise embodiment of the invention herein disclosed without departing from the spirit of the same.

50 In the drawings accompanying this specification:

55 Figure 1 is a diagrammatic side elevation of a flat car showing a plurality of superposed boxes of freight anchored to the car—with parts broken away and in sec-

tion to more clearly indicate the application of the device.

Figure 2 is a plan view of the same.

Figure 3 is a side elevation of a modification in the method employed to secure the freight to the anchoring devices.

Figure 4 is a plan view showing the freight anchored to the car as indicated in the preceding figure.

Figure 5 is a perspective view of the floor anchoring device.

Figure 6 is a plan view of the same.

Figure 7 is a modification or co-operating anchoring device employed between superposed boxes or crates.

Figure 8 is a plan view of the same.

Referring now to the letters of reference placed upon the drawings:

A denotes a flat car. B—B indicate a plurality of boxes or crates loaded upon the car. C designates the floor anchoring device consisting of a plate D provided with a plurality of preferably chamfered apertures D¹, for the passage of spikes or screws by which the device is secured to the deck of a flat car. Projecting upwardly and centrally from the base plate are spaced posts E—E connected by a bar F integral with the posts E reinforced below by an upstanding flange G integral with the plate D, which is provided on one side of the posts with upstanding and downwardly projecting sharp pointed studs H, adapted to be embedded in the deck of the car and wall of the box overlapping the plate. In anchoring the freight to the car deck the upstanding posts E of the device are placed adjacent to the walls of the boxes at each side and end of the latter,—with the boxes resting on the studded portion of the plates,—the studs thereupon under the weight of the boxes being driven into the walls of the latter and also in the car deck;—the floor plate being also spiked to the deck of the car.

When it is desired to load the cars with superposed boxes a corresponding co-operating element D^a shown in Figure 7 is employed with its laterally projecting spike plate D^b interposed between the top and bottom of the respective superposed boxes—the weight of the upper box causing the spikes H of the device to embed themselves in the walls of the upper and lower boxes as will be readily understood. Projecting downwardly from the plate D^a in the co-

operating device are spaced posts E^a connected together by a cross bar F^a with a reinforcing flange G^a similar to the flange G shown in Figure 5.

5 To the cross bars F and F^a is connected a sheet metal strap I looped around the bars and secured by a suitable sealing device J diagrammatically indicated in Figures 1 to 4.

In carrying out the method of loading 10 and anchoring the boxes shown in Figures 1 and 2 the boxes are laid directly upon a car in pairs end to end a plurality of the floor plates being first secured to the deck of the car with their upstanding posts adjacent to 15 the ends and against the side walls of the boxes,—the boxes resting upon the studded plate of the device.

Directly above the anchoring devices upon 20 the top of the row of boxes are placed the co-ordinating devices shown in Figure 7,—and upon the sharpened studs of the latter are loaded four superposed boxes, the weight 25 of which causes the sharpened studs to embed themselves in the walls of the upper and lower boxes.

The anchoring devices secured to the car 30 deck are then connected to those above by metal straps I looped around the respective cross bars F and F^a the looped ends being secured by a suitable sealing device J, dia- 35 grammatically indicated in the first four figures of the drawings. Other metal straps I¹ are then connected with the devices placed between the boxes and extend over the top 40 of the upper boxes to be secured to like de- 45 vices on the opposite side;—the same method being also employed for connecting the anchoring devices placed at each end of the boxes.

40 In the modification in the method of anchoring shown in Figures 3 and 4, the longitudinally running straps I¹ extend from end to end of two sets of boxes and are connected to the devices located between the upper and lower tiers at each end of the car and these are in turn connected with the floor plates secured to the deck at each end 45 of the flat car.

By the employment of this device relatively large and heavy boxed freight may be 50 securely anchored to the car and held against skidding while in transit.

Having thus described our invention what we claim is:

1. An anti-skid anchoring device for 55 freight consisting of a plate having a plurality of studs projecting from the plate, with an integral loop portion extending at right angles to the plate to receive the end 60 of an anchoring strap.

2. An anti-skid anchoring device for 65 freight consisting of a plate having a plurality of sharp pointed studs projecting from one side of the latter and with an integral looped portion extending from the plate at 70 right angles thereto to receive the end of an anchoring strap.

3. An anti-skid anchoring device for 75 boxed freight consisting of a plate having a plurality of projecting studs adapted to be 80 embedded in the walls of boxes containing freight, said plate having an integral pro- 85 jecting right angle portion adapted to overlap the side walls of said boxes and to receive the end of an anchoring strap connected therewith; and means whereby said plate may be attached to a car floor to se- 90 cure the boxes against lateral or longitudinal movement.

4. An anti-skid anchoring device for 95 boxed freight consisting of a plate having a plurality of studs projecting from opposite sides of said plate with integral posts spaced apart and joined together by a connecting bar adapted to overlap the side walls of the 100 freight boxes and to receive the end of a metal strap looped around said connecting bar and extending over the top of the boxes for connection with like devices on the opposite sides of said boxed freight.

5. An anti-skid anchoring device for 105 boxed freight consisting of a plate having a plurality of studs projecting therefrom for embedding in the walls of boxes containing freight resting thereon, said plate being also perforated for the passage of spikes, whereby the device is engaged to the deck of a car, said plate having an up- 110 standing looped portion to receive a metal strap engaged therewith and overlapping the walls of the boxes for engagement with devices of like character on the opposite side of the boxed freight.

In testimony whereof, we sign this specification.

ISADOR LEO FRIEDLAENDER.
STEPHEN J. MARX.
